UNITED STATES PATENT OFFICE.

JOHN NAGY, OF WEST VIEW, PENNSYLVANIA, ASSIGNOR TO PITTSBURGH STAMP COMPANY, OF PITTSBURGH, PENNSYLVANIA, A CORPORATION OF PENNSYLVANIA.

STAMPING-MACHINE.

1,394,333.

Specification of Letters Patent. Patented Oct. 18, 1921.

Application filed July 14, 1921. Serial No. 484,625.

To all whom it may concern:

Be it known that I, JOHN NAGY, a citizen of the United States, residing at West View, in the county of Allegheny and State of 5 Pennsylvania, have invented certain new and useful Improvements in Stamping-Machines, of which the following is a specification.

This invention is for a device for marking 10 articles, and relates particularly to a machine for marking or embossing characters on sheet metal articles, such as cans, can covers, caps, etc.

The primary object of the invention is to 15 provide improved means for holding the co-operating type members comprising dies and matrices, having corresponding projecting and recessed characters respectively, and improved means for insuring proper positioning of the dies and matrices.

My invention may be understood from the accompanying drawings, in which:

Figure 1 is an end view of the type carrying means and type;

Fig. 2 is a section on line II-II of Fig. 1;

Fig. 3 is a horizontal section on line III-III of Fig. 1;

Fig. 4 is a perspective view of one of the 30 type;

Fig. 5 is a plan view of a part of the bed of the machine;

Fig. 6 is a perspective view of another form of type.

In the drawings, A represents the upper 35 movable type carrying member or plunger of a stamping machine, and B is the lower fixed supporting member or bed. The movable member A includes a rod 5 having a block 6 on the lower end thereof. The block 6 has a channel or guideway 7 in its lower face which has undercut or rabbeted sides. Slidable within the block 6 is a type carrying block 8. The type carrying block has a 40 channel cut in its upper face and a type receiving slot 9 cut in it. One side of this slot is provided with serrations 10 which form V-shaped grooves along that side of the slot.

Projecting through one side of the block 50 6 and having its inner end arranged to project into a bore in the type-carrying block 8 is a pin 12 which is urged inwardly by a spring means at 13. This pin serves to assist in locating the type carrying member in 55 place, and provides means for detachably

retaining it in place after it has been properly positioned.

The type carrying block 8 may receive either the dies or the matrices, and I have shown matrices 14 retained therein. The lower end of each matrix 14 has a recessed character therein. At the upper end of each matrix are laterally projecting lugs 14^a and 14^b. The lug 14^b is considerably thicker than the lug 14^a, as shown in Figs. 2 and 4, 60 for the purpose of enabling the typesetter, by feeling the lugs, to readily determine in what position to place the type. To further insure proper positioning of the type, each matrix has a V-shaped projecting portion 70 14^c adapted to fit into the correspondingly shaped groove in the type receiving slot 9. The lug 14^a is designed to rest on the bottom of the channel in block 8, while the flat upper end of the matrix is flush with the surface of the block. When in position, as shown in Fig. 1, the matrices 14 are firmly held in place and are prevented from moving up or down.

The member B includes a block 15 having 80 a recess or guideway therein in which is removably set a type carrying block 16, having a cylindrical projection 16^a thereon. In the projection 16^a is a slot 17 having one side 18 thereof serrated to form V-shaped 85 grooves therein. This slot is designed to receive dies 19 which are generally similar to the matrices 14 and which have the characters projecting above the face of the die. One of the dies is shown in Fig. 6. Extending partway along one side of each of the dies is a V-shaped rib 19^a adapted to fit into one of the V-shaped grooves in the type receiving slot 17 and thereby insure proper 90 positioning of the type.

In order to hold the block 16 in such position that the dies will be positioned directly beneath the matrices, a vertically reciprocable pin may be provided at 20. The end of this pin is adapted to engage a hole 100 with which it is brought into register, its operation and construction being similar to that of pin 12. It will be understood that the dies and matrices have corresponding characters, and that they must be accurately 105 positioned.

The removable type holding blocks 8 and 16 enables the type to be removed from the press while retained in the block, whereby other blocks with different types can be in- 110

serted in the press. Accordingly, it is not necessary to take down and set up type every time a change is to be made. The blocks can be easily inserted and removed. 5 They could also be made to hold more than a single line of type by providing additional slots similar to slots 9 and 17. The type members are so arranged that they may be conveniently and accurately positioned, and 10 cannot be turned in the wrong direction when inserted in the holders.

In operation, the sheet of metal, can top, or other article to be marked is positioned between the plunger A and bed B. As the 15 plunger descends, the article is pressed between the dies and matrices, and is embossed with characters corresponding to those on said dies and matrices.

What I claim is:

20 1. A machine for marking articles comprising a plunger member and a bed member, said plunger and said bed member having guideways therein, a type carrying block 25 slidable in the guideway in said plunger, a set of type removably carried in said block, said block and type having coöoperating parts to prevent the type from being inserted in a wrong position, a type carrying block 30 slidable in the guideway of the bed, one end of the guideway and one end of the block having coöoperating locking means therein for holding the block in proper position, a set of type movably carried in said second 35 type carrying block, said block and type also coöoperating to prevent the type from being inserted in a wrong position, one set of type being matrices and the other set being dies.

2. A machine for marking articles comprising a plunger member and a bed member, 40 a type carrying block slidably and removably mounted in each member, type removably retained in each of said type car-

rying blocks, and means for positioning the type carrying blocks in the respective members in which they are mounted, said means 45 being arranged to prevent said blocks from being locked except when they are inserted in proper position, the type carried by one of the blocks being matrices and those carried by the other block being dies. 50

3. A press for marking articles comprising an upper member and a lower member, one of which is movable relatively to the other, the upper member having a guideway therein, a type carrying block slidable 55 in the guideway, said block having a slot therethrough and a recess in its upper face, types passing through the slot and having lugs at their upper ends, said lugs and upper ends being received in the recess on the 60 upper face of the block, the upper ends of the type being adapted to bear against the bottom of the guideway and be flush with the upper face of the block.

4. A press for marking articles comprising an upper member and a lower member, one of which is movable relatively to the other, the upper member having a guideway therein, a type carrying block slidable 65 in the guideway, said block having a slot 70 therethrough and a recess in its upper face, types passing through the slot and having two lugs at their upper ends, one of said lugs being thicker than the other lug, said lugs and upper ends being received in the 75 recess on the upper face of the block, the upper ends of the type being adapted to bear against the bottom of the guideway and be flush with the upper face of the block. 80

In testimony whereof I hereunto affix my signature.

JOHN NAGY.
